(57) **CLAIM**

The ornamental design for a catheter clamping device, as shown and described.

DESCRIPTION

FIG. 1 is a perspective view of the catheter clamping device shown in a release configuration, as viewed from the front, top, and one side thereof.

FIG. 2 is a perspective view of the catheter clamping device of FIG. 1, as viewed from the back, top, and one side thereof. FIG. 3 is a top plan view of the catheter clamping device of FIG. 1, the bottom plan view being identical to the top plan view.

FIG. 4 is a left side elevational view of the catheter clamping device of FIG. 1, and the right side elevational view being a mirror image thereof.

FIG. 5 is a front elevational view of the catheter clamping device of FIG. 1; and,

FIG. 6 is a rear elevational view of the catheter clamping device of FIG. 1.

The broken lines in the drawings illustrate portions of the catheter clamping device that form no part of the claimed design.

1 Claim, 5 Drawing Sheets
